UNITED STATES PATENT OFFICE.

FRANK L. SIMMONS, OF WOONSOCKET, RHODE ISLAND, ASSIGNOR TO THE TAFT-PEIRCE MANUFACTURING CO., OF WOONSOCKET, RHODE ISLAND, A CORPORATION OF RHODE ISLAND.

ALUMINUM BODY FOR MAGNETIC CHUCKS.

Application filed February 26, 1918. Serial No. 219,237.

To all whom it may concern:

Be it known that I, FRANK L. SIMMONS, a citizen of the United States, residing at Woonsocket, in the county of Providence, State of Rhode Island, have invented certain new and useful Improvements in Aluminum Bodies for Magnetic Chucks, of which the following is a specification.

This invention relates broadly to electrical appliances, and more especially to a magnetic chuck.

The principal object of the present invention is to provide a magnetic chuck wherein the pole pieces and cores for the electro-magnets to energize the pole pieces are made from magnetizable material, and the entire housing and support for the pole pieces of the face plate is made from non-magnetic material.

Another and equally important object of the present invention is a magnetic chuck wherein the core pieces for the energizing electro-magnets are supported in place in the housing by molding the housing around the bases of the core pieces.

Another equally important object of the present invention is a face plate for magnetic chucks wherein the core pieces are supported in a face plate frame of non-magnetizable material which is molded around the pole pieces in such manner as to sustain the pole pieces and form the complete face plate of two metals, a magnetic metal comprising the pole pieces, and a non-magnetic metal comprising the frame.

A further and likewise important object of the present invention is a magnetic chuck with a molded body portion of non-magnetic material, comprising a box to enclose the electro-magnetic energizing units, and a face plate carrying pole pieces and adapted to close said box with the pole pieces in contact with the said electro-magnetic units, whereby there is a single water-tight joint in the construction of the housing for the energizing element.

More specifically the present invention comprises an electro-magnetic chuck having a housing of aluminum or other suitable non-magnetic metal, which is molded around the core pieces for the electro-magnetic units in such manner as to render the core pieces and the housing substantially integral, and wherein the framework of the face plate is

likewise aluminum or other suitable non-magnetic material in which is embedded a plurality of spaced apart individual pole pieces in such manner that the face plate likewise comprises a substantially unitary structure.

A further object of the present invention is to provide a magnetic chuck wherein the electro-magnetic member comprises a plurality of pole pieces extending from a base and with the base embedded in the metal of the housing in such manner that the electro-magnetic members and the housing are substantially integral, and with the face plate provided with the pole pieces in direct contact with the ends of the pole pieces of the electro-magnetic member so that the complete magnetic chuck when assembled comprises a substantially continuous metal structure from the surface of a face plate pole piece through to the bottom surface of the housing whereby the chuck is constructed to withstand heavy pressure directly on the pole pieces. The preceding object of the present invention is an improvement on certain features of my application for patent Serial No. 190,689, filed September 11, 1917.

A still further and equally important object of the present invention is to provide a magnetic chuck having a face plate composed of pole pieces of tree-like conformation comprising a body portion and extensions on opposite sides of said body portion, with the extensions of one pole piece interspersed between the extensions on the adjacent pole piece and electro-magnetic means for magnetizing adjacent pole pieces as opposite magnetic poles.

Another object of the present invention is a magnetic chuck having the entire face plate composed of transverse interspersed pole pieces supported in non-magnetic material whereby the effective magnetism is concentrated over the work face of the face plate.

Other and further objects of the present invention will in part be obvious and will in part be pointed out hereinafter in the specification following by reference to the accompanying drawings wherein like parts are represented by like characters throughout the several figures thereof.

Figure 1 is a plan view of the magnetic

chuck showing a portion of the face plate removed.

Figure 2 is a section taken on line A—A of Figure 1.

5 Figure 3 is a sectional view taken on line B—B Figure 1.

Figure 4 is a perspective view of one core piece for the electro-magnet member and shows the core pieces extending from the 10 base.

Figure 5 is a perspective view of a coil adapted to slip over the core pole pieces.

Figure 6 is a perspective view of one of the surface plate pole pieces.

15 Figure 7 is a plan view of the pole piece shown in Figure 6.

Figure 8 is an elevational view of this pole piece.

20 Figure 9 is an end view of the same pole piece.

Figure 10 is a diagrammatic illustration of the wiring as connected for a 220 volt circuit.

25 Figure 11 is a diagrammatic view of the wiring as connected for a 110 volt circuit.

Figure 12 is a modified form of face plate pole pieces of such conformation that but two dies are necessary to produce the forging for all of the pole pieces.

30 Figure 13 is another modified form of pole pieces wherein but two dies are required to produce all the pole pieces.

Heretofore in the art it has been customary to utilize the housing for the coils as one element in the magnetic circuit so that the coil post of the core piece which terminated in pole pieces at the face plate was one leg of the magnetic circuit and the framework or housing, which contacted with the frame 35 of the face plate, was the other leg of the magnetic circuit. Magnetic chucks in substantially all applications for use are mounted on the iron or steel beds of machine tools, with the bed of the chuck on the bed of the tool and the work in contact with the cutting or grinding member of the tool. Where the lines of magnetism flow around the housing to certain poles in the face plate it is evident that the magnetic circuit 40 through the bed of the machine, the frame of the machine, and the cutting tool, will carry a certain shunted magnetic force. The cutting tools are usually hardened steel which when once magnetized becomes a permanent 45 magnet, therefore in this type of magnetic chuck the tools become magnetized and tend to collect chips which very greatly interferes with the proper operation of the tool. It has also become customary heretofore in the 50 magnetic chuck art to provide face plates with pole pieces of relatively straight sided constructions whereby considerable areas of the face plate have been ineffective as holding areas.

60 65 The present invention overcomes the diffi-

culties with the known prior art by providing a magnetic chuck wherein the magnetizable elements are arranged compactly and supported rigidly upon but spaced apart from the bed of the machine tool with which the chuck is being used. This may be accomplished in various ways, the preferred form of construction, however, being to provide a housing of non-magnetic material, preferably aluminum, which supports the

70 operative elements of the chuck. In the preferred construction the cores for the electro-magnetic unit comprise a member made of special magnet mild steel formed with a base portion and a plurality of outstanding webs which are transversely arranged upon and at right angles to the base portion with these outstanding webs parallel one to

75 another and being adapted to support elongated coils which are constructed to fit over these members so that there is an individual coil for each pole piece. This construction enables standardization of parts which facilitates manufacture and also facilitates re-

80 pairs should any coil become defective. The base of this core piece is embedded in the 85 base of the housing which may be cast around the core piece to comprise an open rectangular box surrounding the electro-

90 magnetic element. The face plate, which facilitates manufacture and also facilitates re-

95 pairs should any coil become defective. The base of this core piece is embedded in the base of the housing which may be cast around the core piece to comprise an open rectangular box surrounding the electro-

100 magnetic element. The face plate, which comprises the lid for this box, is composed of face plate pole pieces which on their under side are adapted to contact with the outstanding core pole pieces that carry the coils.

105 These face plate pole pieces are so constructed as to be formed of drop forgings and preferably are Swedish or Norway iron which possesses but little residual magnetism so that as soon as the current is cut off the magnetism in the chuck ceases. It is particularly desirable that the entire effective magnetized zone of the face plate shall be operative as a holding surface. To this end the face plate pole pieces are provided on their upper sides with tree-like conformations with the branches from one pole interspersed between the branches of the adjacent pole. A uniform space between these 110 tree-like conformations is filled with non-magnetic metal and the lines of magnetic force from one pole piece to another pass through the air over the face plate or when a piece of work of iron or steel is laid on the face plate, such piece of work comprises an armature through which the magnetic circuit is closed. In the present form of the invention, except for the poles, the entire face plate is made of non-magnetic material, such as aluminum.

115 120 By the foregoing construction it will be noted that the entire effective working elements of the chuck are supported by non-magnetic material, in the present case aluminum, and in which the magnetizable elements are embedded by molding the alu-

125

130

minimum around these parts. After the core pole pieces are set in the body of the chuck the side walls and the tops of the body and the cores are brought substantially to a common plane by grinding or other suitable method. Likewise both sides of the face plate are ground or similarly treated to provide relatively smooth parallel surfaces. Where the parts are ground, as specified, the aluminum being slightly softer than the core pole pieces, grinds slightly deeper so that when the face plate is bolted in position on the housing an intimate contact is made between the face plate pole pieces and the core pole pieces and sufficient space is left between the tops of the side walls and the frame for the face plate to permit introduction of a thin gasket of paper, or other material, whereby a water-tight joint is provided. It will also be noted that there is only one joint to be waterproofed in order to completely seal the housing. By embedding the core piece in the housing of non-magnetic metal, the magnetic circuit is spaced apart from the bed of the machine tool and at the same time a firm metal to metal foundation is established between the work faces and the bed of the machine tool.

Referring to the drawings and more particularly to Figures 1 to 5 inclusive, the core piece 1 is preferably cast of special mild magnet steel and comprises a base 2 having outstanding ledges 4 and being provided with a plurality of parallel pole pieces 5. These core pieces preferably are made up in units with eight pole pieces on each unit and chucks of various dimensions in length may be manufactured by assembling a plurality of these core sections preferably end to end. At suitable intervals the outstanding ledges are recessed as at 6 to provide sufficient space between the base ledge and assembly screws which will be later referred to.

In Figure 1 there is illustrated a chuck made up to include two core sections or 16 pole pieces. These core sections are supported in a proper mold and a housing or body of non-magnetic metal, preferably aluminum, is cast around the pole pieces with the ledges 4 embedded in the base of the housing and with the sides of the housing spaced apart from the core pieces 5 a sufficient distance to allow clearance for the energizing coils, later to be more specifically described.

The cast housing is machined to provide a finished article and is formed with ledges 7 on the end of the chuck which ledges are adapted to comprise members which facilitate the clamping of the chuck to a suitable machine frame. The upper end of the pole pieces 5 and the edges of the sides of the box or housing 8 are machined and ground to a substantially common plane. The side walls

are provided, in the molding or by drilling, with suitable openings 9 running from the base of the housing to the top edge of the side walls and comprising openings for the assembly screws 10.

The face plate (Figs. 1, 6 to 9 inclusive) is comprised of a plurality of pole pieces 11 which preferably are drop forgings of Norway or Swedish iron that are supported by being surrounded with non-magnetic metal, in the present case aluminum, or the like. These pole pieces preferably are tree-like in form having a body 12 from which extend projections 14 that are substantially the length and the width equal to the width of the body portion. Alternate pole pieces are of alternate construction in such manner that the projections from one pole piece are interspersed between the projections of the adjacent pole piece with a constant distance between the outline of the pole pieces at the surface of the face plate 15. In forming these pole pieces by drop forging it is convenient to provide angular faces 16 and 17 on the ends of the pole pieces with projections 18 between the faces 16 and 17. When the pole pieces are properly assembled with the edges spaced apart, as specified, in a suitable mold or otherwise, the non-magnetic metal, preferably aluminum, is molded around the pole pieces in such manner that the pole pieces have their sides completely embedded in this metal and because of the conformation of the pole pieces it will be seen that they are securely held against moving in any direction. Where aluminum is used it is desirable to provide inserts 19 of harder metal, such as iron, to comprise the nuts into which the assembly screws 10 may be threaded. After the face plate has been formed it is preferably machined and ground on both the upper and lower surfaces so that the upper surface discloses a conformation of nested three-like pole pieces, (Fig. 1) while the lower surface discloses oval shaped pole piece portions which are adapted to set directly over and in contact with the ends of the pole pieces 5 when the face plate is positioned on the housing as indicated in Figure 2, or the right end portion of Figure 1. It has been found that in the grinding of the joint between the face plate and the housing that the aluminum grinds slightly deeper than the iron so that when the pole pieces in the face plate are in contact with the ends of the pole pieces of the core there is a slight space between the aluminum frame of the face plate and the side walls of the housing.

This slight space is desirable in affording sufficient room to provide a water-proofed paper or other suitable gasket on this joint so that when the parts are assembled the face plate pole pieces and the core pole pieces are in contact and the joint between 130

the housing and the face plate is water-proofed.

As previously stated each core pole piece 5 is adapted to carry an electro-magnetic 5 coil 20 which are of oval cross-section and are suitably insulated from the core pieces. These coils are connected (Figs. 10 and 11) in such manner that the current flows in one direction around one coil and in the 10 opposite direction around the adjacent coil. When the chuck is energized it therefore is clear that a plurality of magnetic circuits are established whereby the pole pieces in the face plate are of alternate magnetic 15 signs, as indicated in Figure 1, and the return circuit for the magnetism is completed through the base 2 of the core pieces. This provides a very compact electro-magnetic unit whereby the tendency of shunt magnetic 20 circuits is reduced to a minimum. There is substantially no air leakage through the tops of metal work carried on the face of this chuck and where the chuck is used on a milling machine, the chips from 25 the cutter may easily be brushed from the surface of the work. With prior art chucks wherein the cutting tool and machine frame have formed a shunt magnetic circuit, in substantially all cases chips stick to the work 30 face and more or less of the chips are carried on the cutting tool.

The chuck may be provided with a suitable switch 21 that is provided with four terminals 22 and 24, as indicated in Figures 35 10 and 11. It will be noted that the terminals 24 are the terminals connected to the outside circuit and the terminals 22 may be connected together thereby throwing the entire set of coils in series to enable the chuck 40 to be used on 220-volt circuit or the terminals 22 may be individually connected with the terminals 24 whereby the coils are in multiple and adapted to be operated on a 110-volt circuit. In practice it may be desirable 45 to accurately position work on the chuck face and for this purpose a back strip 25 of cold rolled steel is fastened to the edge of the face plate outside of the pole piece zone. This back strip is permanently 50 secured in position by machine screws the heads of which are flush with the top of the back strip. In order to provide an adjustable member against which work may be positioned a movable back rest 26 is also provided. This back rest comprises bifurcated 55 legs 27 which are clamped securely in position by means of stub bolts 28 carried by the back side wall of the chuck. It may also be desirable to reinforce the face plate 60 and to this end brass screws 29 may be passed through under the pole pieces and threaded into the edge of the aluminum facing for the face plate, as indicated in dotted lines Fig. 1.

65 In order to facilitate manufacture of the

chucks it may be desirable to provide the pole pieces of such conformation that but two dies are necessary for all the pole pieces in the face plate. Such constructions and pole piece conformations are indicated in 70 Figures 12 and 13. One die would be required to produce the end pole pieces 30 and a different die would be required to produce the intermediate pole pieces 31 or 32 as the case might be. 75

Attention is particularly directed to the simplicity and rigidity of the herein disclosed chuck and it is to be noted that there are but three major elements in the make-up of the device, one element comprising 80 the housing and core piece, the other element being the coil sections adapted to fit upon the core pieces and the third element comprising the face plate constructed to be secured to the housing. 85

Realizing that my invention may be carried out in structures other than those specifically disclosed herewith I desire that this disclosure be understood as illustrative and not to be taken in the limiting sense. 90

Having thus described my invention, what I claim is:

1. In a magnetic chuck the combination of a housing comprising an open box of non-magnetic material, a core piece of magnetizable material partially embedded in said housing, face plate pole pieces of magnetizable material, a frame of non-magnetizable material embedding and closing the sides of said pole pieces, and coils carried by said core piece and adapted when energized to magnetize said core piece and said face plate pole pieces. 95

2. In a magnetic chuck the combination of a housing comprising an open box of non-magnetic material, a core piece of magnetizable material partially embedded in said housing, face plate pole pieces of magnetizable material, a frame of non-magnetizable material embedding and closing the sides of said pole pieces, lugs on said pole pieces to restrain said pole pieces from movement in said material, and coils carried by said core piece and adapted when energized to magnetize said core piece and said face plate 100 pole pieces. 110

3. In a magnetic chuck the combination of a housing comprising an open box of non-magnetic material, a core piece of magnetizable material having the base thereof embedded in the base of said housing, face plate pole pieces of magnetizable material, a face plate frame of non-magnetizable material completely surrounding the sides of each pole piece and supporting each pole 115 piece in such manner that when said face plate is in position on said housing the face plate pole pieces are in contact with said core piece, and energizing coils adapted to be carried by said core piece. 120

4. In a magnetic chuck the combination of a housing comprising an open box of aluminum, a core piece of magnetizable material having the base thereof embedded in the base of said housing, face plate pole pieces of magnetizable material, a face plate frame of aluminum completely surrounding the sides of each pole piece and supporting each pole piece in such manner that when said face plate is in position on said housing the face plate pole pieces are in contact with said core piece, and energizing coils adapted to be carried by said core piece.
5. In a magnetic chuck the combination of a housing comprising an open box of non-magnetic material, a core piece, a base on said core piece, pole pieces outstanding from said base, a face plate comprising a frame of non-magnetizable material, face plate pole pieces of magnetizable material embedded within and with the sides thereof surrounded by said face plate frame whereby the face plate pole pieces are positioned to correspond to the poles on said core piece, and energizing coils adapted to be carried by the said core pieces.
6. In a magnetic chuck the combination of a unitary aluminum body comprising an open box of non-magnetic material to constitute the housing for the chuck, a core piece of magnetizable material having the base of said core piece embedded within said aluminum body, poles outstanding from the said base and separated from the side walls of said aluminum body, a face plate comprising an aluminum frame, face plate pole pieces of magnetizable material embedded within said aluminum frame and spaced apart to correspond to the poles on the core piece, and energizing coils carried by said core piece.
7. In a magnetic chuck in combination an aluminum body comprising a unitary open box of non-magnetizable material, a core piece having a base provided with extensions, the base of said core piece being embedded within said aluminum body portion, whereby said extensions securely lock said base in position, poles extending from said base, a face plate comprising a frame of aluminum which surrounds and supports the individual face plate pole pieces, coils on the poles of the core piece, and means to secure said face plate to said housing.
8. In a magnetic chuck the combination of an aluminum body comprising the housing, a core piece having the base thereof embedded in said aluminum body, flat pole pieces extending outwardly from said base, said pole pieces being substantially parallel and extending crosswise of the longitudinal axis of the housing, the ends of said pole pieces being substantially coplanar with the edges of the sides of the body portion, a face plate comprising an aluminum frame, face plate pole pieces embedded in said aluminum frame and being separated one from another by portions of said aluminum frame, said face plate being substantially flat and the pole pieces in said face plate being positioned to contact with the pole pieces on the core when the face plate is in position to cover said housing, coils on the core pole pieces, and means to secure the face plate to said housing.
9. A magnetic chuck comprising an aluminum body portion, an aluminum face plate, an iron core piece around the base of which said aluminum body is molded, outstanding pole pieces carried by the base of the core piece and separated from the sides of the aluminum body, and iron face plate pole pieces around which the aluminum face plate frame is molded, the parts being constructed and arranged so that the chuck is substantially composed of magnetizable material around which the supporting housing and face plate of non-magnetizable material is molded, and energizing coils adapted when suitably energized to magnetize the said pole pieces.
10. As an article of manufacture a magnetic chuck body comprising suitable pole pieces, electro-magnetic means which when energized are adapted to magnetize said pole pieces, and aluminum means comprising a housing for supporting the said pole pieces and the said electro-magnetic means.
11. As an article of manufacture a magnetic chuck comprising work-face pole pieces, electro-magnetic means which when energized suitably magnetize said work-face pole pieces, and non-magnetizable material embedding and supporting said pole pieces and enclosing said electro-magnetic means.
12. As an article of manufacture a magnetic chuck comprising Swedish iron work-face pole pieces, said pole pieces being spaced apart to be magnetically separated one from another, electro-magnetic means which when energized suitably magnetizes the said pole pieces, and a casing of aluminum in which said pole pieces are embedded and which encloses and supports said pole pieces and said electro-magnetic means.
13. As an article of manufacture a face plate for magnetic chucks, said face plate comprising a plurality of face plate pole pieces, and an aluminum frame molded around said pole pieces whereby said pole pieces have their sides completely embedded in the said aluminum frame.
14. As an article of manufacture a face plate for magnetic chucks, said face plate comprising a plurality of face plate pole pieces, and an aluminum frame comprising the sole support for said pole pieces whereby said pole pieces have their sides completely embedded in the said aluminum frame.
15. As an article of manufacture a face plate for magnetic chucks, said face plate

- comprising pole pieces of Swedish iron spaced apart one from another, and a frame work of moldable non-magnetic material cast around the said pole pieces to retain 5 said pole pieces in position and to form a substantially integral member that constitutes said face plate.
16. As an article of manufacture a face plate for magnetic chucks and the like, said 10 face plate comprising a plurality of pole pieces of Swedish iron, said pole pieces having work-faces of substantially tree-like conformation, and having back faces adapted to conform to suitably electro-magnetic energizing means, said pole pieces being arranged in a row, and a supporting frame of non-magnetizable metal molded around said pole pieces whereby said face plate is substantially integral unit.
17. As an article of manufacture a face plate for magnetic chucks and the like, said 15 face plate comprising a plurality of pole pieces of Swedish iron, said pole pieces having work-faces of substantially tree-like conformation, and having back faces adapted to conform to suitable electro-magnetic energizing means, said pole pieces being arranged in a row, and a supporting frame of non-magnetizable metal comprising the sole support 20 for said pole pieces whereby said face plate is a substantially integral unit.
18. As an article of manufacture a face plate for magnetic chucks and the like comprising a plurality of pole pieces having 25 work-faces of tree-like conformation whereby the branches from one pole piece are adapted to extend between the branches of an adjacent pole, said pole pieces being set parallel one to another to constitute a row, 30 and an aluminum plate of the same thickness as said pole pieces and enclosing and embedding each pole piece whereby substantially the entire face plate is composed of the Swedish iron pole pieces and the said aluminum supporting plate.
19. As an article of manufacture a body portion of a magnetic chuck comprising a core piece of special magnet-mild-steel and being provided with outstanding pole pieces, 35 and a housing of aluminum molded around the base of said core piece and with the pole pieces separated from the sides of the housing whereby the core piece and the housing comprise a substantially unitary structure.
20. As an article of manufacture a body for a magnetic chuck comprising a core piece of magnet-mild-steel, a housing of non-magnetic material molded around the base 40 of said core piece whereby the said core piece and said housing comprise substantially a unitary structure.
21. As an article of manufacture a core piece for magnetic chucks and the like, said core piece comprising a base, a plurality of 45 flat pole pieces outstanding from said base and at substantially right angles thereto, the mid planes of said pole pieces being substantially parallel.
22. A magnetic chuck comprising a plurality of face plate pole pieces, means to support said pole pieces, and electro-magnetic means to suitably magnetize said pole pieces, the entire work surface of the face plate comprising a series of spaced-apart interlocked pole pieces of tree-like conformation with branches of one pole piece extending between the branches of the adjacent pole piece.
23. A magnetic chuck comprising a plurality of face plate pole pieces, non-magnetic material comprising the means to support said pole pieces, and electro-magnetic means to suitably magnetize said pole pieces, the entire work surface of the face plate comprising a series of spaced-apart interlocked 75 pole pieces of tree-like conformation with branches of one pole piece extending between the branches of the adjacent pole piece.
24. A magnetic chuck comprising in combination a housing of aluminum, a face plate frame of aluminum, a core having the base thereof embedded in the base of the said housing, said core having a plurality of outstanding pole pieces, face plate pole pieces having a width greater than the thickness 90 of the core pole pieces and embedded within and carried by said face plate frame and in contact with the poles of the said core, the surface of the face plate poles being substantially coplanar with the surface of the 95 face plate frame, and means capable when electrically energized of producing a series of magnetic circuits with each circuit thereof having a common magnetic line path with the next adjacent circuit and each circuit 100 including a pair of face plate pole pieces whereby a plurality of complete closed magnetic circuits is formed when a magnetizable work piece rests on the surface plate.
25. In a magnetic chuck a work-face comprising a plurality of interlocking pole pieces arranged side by side with the length of the pole pieces extending across the said work-face, each pole piece presenting a holding surface comprising a straight trunk 105 portion with square blocks on each side of said trunk portion to provide a tree-like conformation, means capable when energized of magnetizing said pole pieces to constitute alternate magnetic poles of alternate 110 signs, and a neutral frame for supporting said interlocking pole pieces.
26. A face plate for magnetic chucks comprising a plurality of pole pieces and a non-magnetized frame around said pole pieces 115 with portions of said frame extending between said pole pieces to support the same.
27. In a magnetic chuck, the combination of a housing, electromagnetic means within said housing a face plate, a plurality of pole 120 pieces

pieces in said face plate and adapted to be magnetized when said electromagnetic means are energized, and a supporting frame surrounding and extending between said pole 5 pieces in such manner that each pole piece is completely surrounded by said frame.

28. A magnetic chuck comprising in combination a housing, a face plate having a plurality of individual pole pieces mounted 10 therein, said pole pieces comprising substantially straight bar-like body portions with a plurality of arms extending outwardly from said body portions with the arms spaced apart whereby the arms of adjacent pole pieces are interpositioned, said body portions comprising the under part of the pole pieces and the spacing between adjacent pole piece body portions being greater than the spacing between adjacent pole 15 pieces arms whereby the magnetic field is concentrated between the arms when the chuck is energized, core pole pieces beneath the face plate pole pieces and with the upper ends of the core pole pieces in contact with 20 said body portions of the face plate pole pieces, and coils for energizing the said core pole pieces.

29. A magnetic chuck comprising in combination a housing, a face plate, a plurality 30 of face plate pole pieces mounted in the said face plate, said face plate pole pieces comprising bar-like body portions and arms extending from said body portions, said arms being spaced apart and being arranged in 35 such manner that the arms from adjacent pole pieces are interpositioned, non-magnetic material between the said pole pieces, said body portions comprising the under part of the pole pieces and being arranged 40 parallel with the spacing between adjacent body portions being greater than the spacing between adjacent arms whereby the magnetic field is concentrated between the arms, and an electro-magnetic means for 45 energizing the said pole pieces, the said electro-magnetic means comprising a core piece on the housing and carrying a plurality of upstanding core pole pieces adapted to contact with the under part of the said 50 body portions of the face plate pole pieces, and coils adapted when energized to magnetize the said core pole pieces.

30. As an article of manufacture a pole piece for magnetic chucks comprising a bar-like body portion adapted to form the under part of the said pole piece, a plurality of outstanding arms extended on each side of the said body portion and spaced apart in such manner that pole pieces of the construction specified may be arranged with the body portions substantially parallel and the outstanding arms of the adjacent pole pieces interspaced, and with the distance between the arms of adjacent pole pieces 65 being less than the distance between adja-

cent body portions whereby a magnetic field may be concentrated between the arms when the poles are in use on a magnetic chuck.

31. A magnetic chuck having a portion of a work-holding face composed of a plurality 70 of identical pole pieces, projections on the pole pieces, and means to support the pole pieces, with the projections of adjacent pole pieces interspaced.

32. A magnetic chuck having a work- 75 holding face comprising a plurality of pole pieces of identically the same size and shape arranged one adjacent to another with extensions from said pole pieces arranged in such manner that the extensions from one 80 pole piece lie between the extensions of an adjacent pole piece.

33. A magnetic chuck having a work-holding face comprising a plurality of pole 85 pieces of identically the same size and shape arranged one adjacent to another, non-magnetic material surrounding each pole piece, and electromagnetic means capable when energized to magnetize adjacent poles with opposite magnetic signs. 90

34. A magnetic chuck having a work-holding face comprising a plurality of identical individual pole pieces having body 95 portions and extensions from the body portions, with the extensions from one pole piece lying between the extensions of the adjacent pole piece, and non-magnetic material surrounding said pole pieces and isolating the pole pieces one from another.

35. A magnetic chuck having a work- 100 holding face comprising a plurality of identical individual pole pieces having body portions and staggered extensions from the body portions, with the extensions from one pole piece lying between the extensions of the adjacent pole piece, and non-magnetic material 105 surrounding said pole pieces and isolating the pole pieces one from another.

36. A magnetic chuck having a work-holding face comprising a plurality of identical individual pole pieces having body 110 portions and extensions on the work-face side of the body portions, with the extensions from one pole piece lying between the extensions of the adjacent pole piece at the 115 work face, and non-magnetic material surrounding said pole pieces and isolating the pole pieces one from another.

37. A magnetic chuck having a work-holding face comprising a plurality of identical individual pole pieces having body 120 portions and extensions from the body portions, with the extensions from one pole piece lying between the extensions of the adjacent pole pieces, and non-magnetic material 125 surrounding said pole pieces and isolating the pole pieces one from another, the back of said pole pieces being of a different pattern from the pattern on the work face.

FRANK L. SIMMONS.
